UNITED STATES PATENT OFFICE

CHARLES H. WEISGERBER, OF PHILADELPHIA, PENNSYLVANIA

DESIGN FOR A COMBINED TOY STAGE AND STAGE SETTING THEREFOR OR SIMILAR
ARTICLE

Application filed April 2, 1929. Serial No. 30,721. Term of patent 14 years.

To all whom it may concern:

Be it known that I, CHARLES H. WEISGERBER, a citizen of the United States, residing at Philadelphia, in the county of Philadelphia and State of Pennsylvania, have invented a new, original, and ornamental Design for a Combined Toy Stage and Stage Setting Therefor or Similar Article of which the following is a specification, reference being had to the accompanying drawing, forming a part thereof.

The drawing is a front elevational view, in perspective, of a combined toy stage and stage setting therefor showing my new design.

I claim:

The ornamental design for a combined toy stage and stage setting therefor, or similar article, as shown.

CHARLES H. WEISGERBER.
